UNITED STATES PATENT OFFICE.

NATHAN M. FEIGELY, OF IOLA, KANSAS.

VALVE-BAG.

1,287,935.

Specification of Letters Patent.

Patented Dec. 17, 1918.

Application filed November 21, 1916. Serial No. 132,516.

To all whom it may concern:

Be it known that I, NATHAN M. FEIGELY, citizen of the United States of America, and a resident of Iola, in the county of Allen 5 and State of Kansas, have invented new and useful Improvements in Valve-Bags, of which the following is a specification.

This invention relates more particularly to bags which are used for shipping cement, 10 and known in the trade as cement bags, although it is to be understood that the invention may be applied to other packaging bags if found desirable, and I do not wish to be understood as restricting myself specifically to cement bags by referring to the 15 same in the following description.

The objects of the invention are to provide an improved valve bag which will not spill the contents; to provide a valve which 20 will close naturally and automatically; to avoid changing the capacity of the bag in forming the valve therein; to retain the full strength of the bag; to support the bag by its gathered or tied end upon the filling 25 spout while being filled; to secure simplicity of construction and operation, and to obtain other advantages and results as may be brought out in the following description.

Referring to the accompanying drawing, 30 in which like numerals of reference indicate the same parts throughout the several views,

Figure 1 is a side elevation of a cement bag having its mouth tied closed, and shown in position for filling upon a filling spout;

Fig. 2 is a side view of the same with the mouth open and showing the valve opening distended for greater clearness;

Fig. 3 is a perspective view of a portion 40 of the inside of the bag showing the valve opening distended;

Fig. 4 is a transverse sectional view through one of the rivets at the end of the valve opening, and

Fig. 5 is a transverse cross-sectional view 45 transversely through the distended valve opening.

In the specific embodiment of the invention illustrated in said drawings, the reference numeral 1 indicates a bag having as 50 usual a mouth 2 and preferably made from fabric, such as coarse or heavy cloth. As is usual in the construction of such bags, the cloth or material of which the bag is made, is sewed together, as at 3, forming a seam 55 4 down one side of the bag and across the

bottom. It is to be understood that the marginal portions of the cloth are brought flatwise together, in making this seam, and the stitching runs along said margins at a distance from the edges thereof holding the 60 two portions of the material together. This leaves marginal portions or flanges 5, 5 of the material between the free edges thereof and the stitching, said flanges, in use, being 65 upon the inside of the bag.

Near the mouth of the bag, said flanges are, for a certain length, left unstitched, forming thereby a valve opening or slot 6 through the seam of the bag, by means of which the bag may be filled after the mouth 70 of the bag is tied up. As shown, a suitable wire or other tie 7 is provided adapted to pass around the neck of the bag or that portion thereof adjacent the mouth and close the mouth. It will be obvious that tying 75 the mouth in this manner gathers or puckers the material together, causing portions of the material to overlap other portions. I take advantage of this natural puckering of the neck and overlapping of the material to 80 close the valve opening 6 by positioning said valve opening in the neck of the bag rather than elsewhere. Closure of this opening is furthermore secured by the natural tendency of the flanges to lie flatwise together 85 across the same, since they are positively held flatwise together by the stitching 3 at either end of the opening, and although I have shown the valve opening or slot drawn apart or distended in the several views for 90 greater clearness, it is to be understood that the slot is normally closed. As the bag is filled, it is found that the flanges are both turned to one side and held against the wall of the bag by the pressure of the contents, 95 and this tendency to lie against the wall of the bag obviously will lap one of the flanges over the valve opening, effectually sealing the opening against the escape of the cement or other contents of the bag.

Furthermore, the puckering of the neck of the bag as above described relieves the portion of the bag around the valve from any additional strain due to the opening or incontinuity, and lifting or handling the bag 105 tends neither to tear or strain the bag as a result of the opening nor to cause the opening to gap and spill the contents, acting rather to close the slot. Further advantages of my improved valve bag are that it does 110

not change the shape or appearance of the bag and does not change the capacity of the bag at all nor does it require any additional material in manufacture.

- 5 To insure against ripping the seam open, as while the bag is being filled, the stitching at each end of the opening is reinforced in any suitable manner, and in the drawing I have shown a rivet 8 at each end of the opening in the line of stitching. These rivets extend through and securely clamp the flanges together and take substantially the entire strain from the seam when the valve is opened, as when the filling nozzle is inserted.
- 10 15 However, I deem it within the scope of the invention to employ other means than these rivets if so desired for accomplishing the same purpose.

In use, it is to be understood that the bag, 20 being empty, is first tied with the tie 7, completely closing the mouth of the bag. Preferably in tying the bag the tie is placed as close to the valve opening 6 as practicable without interfering with the proper use 25 thereof so as to take full advantage of the puckering caused by said tie. The nozzle 9 of the filling machine is inserted in this valve opening and the bag hangs thereon while being filled. As shown, the nozzle 30 extends well across the bag, supporting the same at the middle and top of the bag, taking advantage of the tied neck which is the most natural and strongest part by which to hang the bag. When the bag is filled it 35 is removed from the nozzle permitting the valve opening to close. To remove or use the contents from the bag, the tie 7 is undone and the mouth of the bag opened giving free access to the interior of the bag.

40 Although I have shown a valve formed by an opening in a seam, between the inwardly projecting flanges thereof, it is to be understood that any common and well-known valve adapted to the purpose may be employed, and I have used the term "valve" herein as including everything of that sort. Other modifications and changes may be made in manufacturing my improved valve 45 bag without departing from the spirit and scope of the invention, and I do not wish to be understood as restricting myself except 50

as required by the following claims when construed in the light of the prior art.

Having thus described the invention, what I claim is.

55

1. A packaging bag having a discharge end adapted to be closed by tying, and a filling valve which closes against discharge through itself located in that portion of the bag which is gathered or puckered by 60 such tying and through which valve the bag may be filled after it is tied.

2. A packaging bag having a discharge end adapted to be closed by tying, and a filling valve which closes against discharge 65 through itself longitudinally located in that portion of the bag which is gathered or puckered by such tying and through which valve the bag may be filled after it is tied.

3. A packaging bag having a discharge 70 end adapted to be closed by tying and a longitudinal side seam, and a filling valve which closes against discharge through itself in said side seam adjacent said discharge end of the bag, whereby in tying said end the 75 gathering or puckering aids in closing the valve.

4. A packaging bag having a discharge end open and unobstructed for substantially 80 the maximum cross-sectional size of the bag, said end adapted to be closed by tying, and a filling valve which closes against discharge through itself located in that portion of the bag which is gathered or puckered by such 85 tying and through which valve the bag may be filled after it is tied.

5. A packaging bag having a longitudinal side seam and having a discharge end open and unobstructed for substantially the maximum cross-sectional size of the bag, said end 90 adapted to be closed by tying, and a filling valve which closes against discharge through itself in said side seam adjacent said end whereby in tying said end the gathering or puckering aids in closing the valve. 95

In testimony whereof I have signed this specification in the presence of two subscribing witnesses.

NATHAN M. FEGELEY.
